US00D781702S

(12) **United States Design Patent** (10) Patent No.: **US D781,702 S**
 Sanfilippo et al. (45) Date of Patent: **** Mar. 21, 2017**

(54) **MATERIAL FOR PACKAGING PRODUCTION**(71) Applicant: **CLEAR LAM PACKAGING, INC.**, Elk Grove Village, IL (US)(72) Inventors: **James J. Sanfilippo**, Barrington Hills, IL (US); **Milorad Radenovic**, Chicago, IL (US); **Jeanne M. Skaggs**, Arlington Heights, IL (US)(73) Assignee: **CLEAR LAM PACKAGING, INC.**, Elk Grove Village, IL (US)(***) Term: **14 Years**(21) Appl. No.: **29/500,458**(22) Filed: **Aug. 25, 2014**(51) LOC (10) Cl. .... **09-03**(52) U.S. Cl. USPC .... **D9/433**(58) **Field of Classification Search**

(74) Attorney, Agent, or Firm — Marshall, Gerstein & Borun LLP

(57) **CLAIM**

The ornamental design for material for packaging production, as shown and described.

DESCRIPTION

The sole FIGURE is a plan view of a material for packaging production showing the new design.

The broken lines represent elements of the material for packaging production form no part of the claimed design.
